US0D1049148S

(12) **United States Design Patent** (10) **Patent No.:** **US D1,049,148 S**
Mairs et al. (45) **Date of Patent:** **** Oct. 29, 2024**

(54) **DISPLAY SCREEN OR PORTION THEREOF WITH A GRAPHICAL USER INTERFACE**

D573,599 S 7/2008 Williams
D593,109 S 5/2009 Danton
D600,248 S 9/2009 Scalisi et al.
D614,191 S 4/2010 Takano et al.
D634,749 S 3/2011 Brown

(Continued)

(71) Applicant: **INSPIRE MEDICAL SYSTEMS, INC.**, Golden Valley, MN (US)

(72) Inventors: **Nicholas Mairs**, Minneapolis, MN (US); **Brody Belland**, St. Louis Park, MN (US); **John Rondoni**, Plymouth, MN (US); **Donovan Fellows**, Lake Elmo, MN (US); **Kathleen Tolmie**, Mendota Heights, MN (US)

FOREIGN PATENT DOCUMENTS

CN 306942282 * 11/2021

(57) **CLAIM**

The ornamental design for a display screen or portion thereof with a graphical user interface, as shown and described.

DESCRIPTION

The FIGURE is a front view of a display screen or portion thereof with a graphical user interface showing our new design.

The outermost broken lines show a display screen or portion thereof and form no part of the claimed design. The remaining broken lines show elements of the graphical user interface that form no part of the claimed design.
